United States Patent Office.

IRA A. NEWHALL, OF CROOKED CREEK, PENNSYLVANIA.

Letters Patent No. 90,462, dated May 25, 1869.

IMPROVED WASHING-MACHINE.

The Schedule referred to in these Letters Patent and making part of the same.

To all whom it may concern:

Be it known that I, IRA A. NEWHALL, of Crooked Creek, in the county of Tioga, and State of Pennsylvania, have invented a new and improved Washing-Machine; and I do hereby declare that the following is a full, clear, and exact description thereof, which will enable others skilled in the art to make and use the same, reference being had to the accompanying drawing, forming part of this specification, in which—

Figure 1 is a vertical longitudinal section of my improved machine, taken through the line $x-x$, fig. 2.

Figure 2 is a detail cross-section of the same, part being broken away to show the construction.

Similar letters of reference indicate corresponding parts.

My invention has for its object to furnish a simple, convenient, and effective washing-machine, doing its work quickly and well, and without injuring the articles being washed; and

It consists in the construction and combination of the various parts of the machine, as hereinafter more fully described.

A represents the box or tub of the machine, which is made rectangular in its general form, and the bottom of which is made concave or semi-cylindrical in form, as shown in fig. 1.

B are two rubber frames, which are placed, one in each end of the box A, and the end-bars of which are pivoted, below their middle points, to the sides of the tub A.

The rubber boards B are formed by pivoting the ends of a system of rollers, b^1 , to the end-bars b^2 , as shown in fig. 1.

The movements of the roller-frame B are limited

by the stops or strips C, attached to the sides of the box A, near its ends, in such positions that the end-bars b^2 of the roller-frames B, when in a vertical position, may rest against them.

The lower ends of the stops C are bevelled off, as shown in fig. 1, so that the roller-frames may take a position parallel with the swinging roller-frame D, when said roller-frame is swung against them.

The roller-frame D is formed by pivoting two rows of rollers d^1 to the side-bars d^2 of said frame.

d^1 is the pivoting-rod, which passes through the side-bars d^2 , and the ends of which work in notches in the upper edges of the sides of the box A, as shown in fig. 2.

The side-bars d^2 are extended upward, and their upper ends are connected by a cross-bar, d^3 , which serves as a handle for operating the machine.

The lower side of the lower cross-bar of the swinging rubber frame D, is rounded off to correspond with the curve of the bottom of the box A, so that the clothes may not get between the said cross-bar and the bottom, and be worn or injured.

Having thus described my invention,

What I claim as new, and desire to secure by Letters Patent, is—

The combination of the roller-frames B, pivoted, below their centres, to the side of the box A, the end-strips C having their lower ends bevelled, and the frame D, provided with two rows of rollers d^1 , all arranged and operating as described, for the purpose specified.
